United States Patent Office

Des. 194,587

Patented Feb. 19, 1963

194,587

MULLION COVER

James C. Waring, Richmond, Va., and Leslie A. Fream, Jefferson County, Ky., assignors to Reynolds Metals Company, Richmond, Va., a corporation of Delaware

Filed Dec. 28, 1961, Ser. No. 68,112

Term of patent 14 years

(Cl. D13—6)

FIG. 1.

FIG. 2.

FIGURE 1 is a fragmentary front perspective view of a mullion cover showing our new design; and,

FIGURE 2 is a front perspective view of the mullion cover taken from the other side and end.

The center thereof is broken away to indicate indeterminate length.

We claim:

The ornamental design for a mullion cover, substantially as shown and described.
